DESIGN FOR A FLOWERPOT HOLDER OR SIMILAR ARTICLE

Rudolph C. Planeta, Roselle, N. J., assignor to Anthony Planeta, Rahway, N. J.

Application March 31, 1941, Serial No. 100,035

Term of patent 7 years

To all whom it may concern:

Be it known that I, Rudolph C. Planeta, a citizen of the United States, residing at Roselle, in the county of Union and State of New Jersey, have invented a new, original, and ornamental Design for a Flowerpot Holder or Similar Article, of which the following is a specification, reference being had to the accompanying drawing, forming part thereof.

Figure 1 is a top plan view, Figure 2, a front elevation and Figure 3, a side elevation of a flowerpot holder or similar articles, showing my new design.

I claim:

The ornamental design for a flowerpot holder or similar article, as shown.

RUDOLPH C. PLANETA.
